UNITED STATES PATENT OFFICE.

FRITZ RITTER von DORMUS AND JULIUS FLEISCHMANN, OF VIENNA, AUSTRIA-HUNGARY.

CONTROLLING DEVICE FOR RADIATORS.

1,084,717.

Specification of Letters Patent.

Patented Jan. 20, 1914.

Application filed November 11, 1910. Serial No. 591,836.

To all whom it may concern:

Be it known that we, FRITZ RITTER von DORMUS, engineer, of Marxergasse No. 1, Vienna, III, and JULIUS FLEISCHMANN, engineer, of Praterstrasse 66, Vienna, II, Austria-Hungary, have invented an Improvement in Controlling Devices for Radiators; and we do hereby declare the following to be a full, clear, and exact description of the invention, such as will enable others skilled in the art to which it appertains to make and use the same.

It is ordinary in the art of heating by steam or other fluid mediums to connect the radiator with the fluid conduit by two separate pipes or branches, in each of which is located a controlling element, whereas in the main conduit between the points at which the branch pipes join the main another valve member is located so that by controlling the latter a flow of the heating medium through the radiator may be effected independent of the direction of the flow in the main, whereby the intensity of the radiator heating is controlled irrespectively of the direction of flow through the radiator.

According to the present invention the control in systems where the heating medium may flow in either direction through the main and the radiator is obtained by a controlling member common for both, the flow branch to the radiator and the return branch. This is rendered possible by leading the medium through the controlling member to and from the radiator. Moreover the controlling member is constructed in such form that when the connection between the main and the radiator is interrupted through it, it will render it impossible for the heating medium to further affect the radiator so that the latter is able to quickly cool off.

In order to obtain the results previously pointed out the controlling member consists preferably of a cylindrical slide valve with two completely supported chambers which are in turn provided with inlet and outlet ports, whereby this valve member is movably disposed in one or two casings which casings are connected with the flow and return flow pipes of the radiator. By properly moving this slide valve into the "hot" position one of these chambers establishes a connection between the flow pipe of the radiator and

the flow branch connecting the valve casing with the main, while the other chamber connects the return branch of the radiator with the return branch from the casing to the main. On the other hand when the slide is moved into the "cold" position the ports of its chamber are vented to the outside, whereby it is rendered impossible that, for instance, steam may leak into the radiator and produce an undesirable slow heating of the radiator.

In order to produce a flow of the heating medium through the radiator when its controlling valve has been properly opened, as mentioned above, the branches connected to the main are, at the points at which they lead into the main, provided in well known manner with nozzles, deflectors or similar means by which a suction or pressure, or also a suction and pressure is exerted upon the contents of the radiator. In order to produce a suction and a pressure and also to permit a flow of the heating medium through the radiator in either direction according to the direction in which the medium flows through the main the nozzles or deflectors are arranged so that the deflector of one branch is directed against one direction of flow and the one of the other branch is directed against the other direction of flow.

Several illustrative embodiments of our invention are represented by way of example in the accompanying drawing, wherein:

Figure 1 is an elevation showing our improved regulator comprising branches for connection to the main heating pipe and radiator, Fig. 2 a transverse section taken mainly on the line A—A in Fig. 1, but distorted in part to follow the apex of the branches 2 and 3, Fig. 3 a transverse section taken partly on the line B—B in Fig. 1, but distorted in part to follow the apex of the branches 7 and 8, Figs. 4, 5 and 6 are longitudinal sections showing the regulator in three different positions; Figs. 7 and 8 are like views showing two modified forms of regulator.

The general construction of the valve as shown in Figs. 1 to 8 is as follows: The pipes 2 and 3 branching from the heating pipe 1 open into the section or box 4 of the valve, while pipes 7 and 8 leading to the

radiator branch off from a second section or box 6 which is separated in space from the former box and rigidly connected therewith by a web 5. A tubular valve or pipe 9, 5 closed at both ends and guided tightly in stuffing boxes, passes through these two sections. This valve is internally divided into two chambers or spaces which are completely separated from one another and, in 10 the illustrative embodiment shown in Figs. 1 to 6, are formed by a second pipe 10 arranged, for this purpose, in the tubular valve in such manner that it leaves free at each of its two ends a space having a diameter equal to that of the internal diameter of the outer pipe or valve 9 and shut off by flanges 11 from the annular chamber between the two pipes. The outer pipe or valve 9 is provided at its two ends with 15 ports 12, 13 and 14, 15, of which the ports 12, 14 can be connected with the outer chamber 16 and the outer ports 13, 15 with the inner chamber 17, their positions being such that the ports 12, 14 of the outer chamber 16 20 register, when the valve is open for heating, as Fig. 4 shows, with the ends of the branch pipes 3, 7 leading to the valve and to the radiator, respectively, while the ports 15, 13 of the inner chamber 17 register with 25 the ends of the branch pipes 8 and 2 leading to the radiator and to the valve, respectively. Therefore, the heating medium, *e. g.* steam, passing from the main pipe 1 into the 30 branch pipe 3 can pass through the port 12 into the outer annular chamber 16 in the valve and thence through the port 14 and the pipe 7 to the radiator, whence it then flows back through the branch pipe 8 and the port 15 into the inner chamber 17 and 35 thence through the port 13 and the branch pipe 2 into the main pipe 1, as indicated by the arrows in Fig. 4. In order, however, more certainly to cause the steam to circulate in the radiator, we provide at the 40 mouths of the branch pipes connected to the pipe 1 curved deflectors 18, 19, of which the one is directed opposite to the direction of flow of the steam and the other in the direction of the flow thereof, so that, on the one hand, steam is directed into the one branch, 45 and in consequence of the flow of the steam, conducted into the radiator and, on the other hand, in consequence of the flow of steam in the main pipe, steam is sucked up out of the other branch at the other deflector, and steam is thereby caused to circulate 50 through the radiator. By suitably shifting the valve axially its ports 12, 14 and 13, 15 can be closed more or less and in 55 this manner the quantity of the steam flowing through the radiator or the intensity of the heat can be regulated. If the flow pipe to the regulator is to be closed without, however, connecting the radiator with the atmosphere and thereby making it cold, the

valve is shifted in the direction of the arrow out of the position shown in Fig. 4 into that shown in Fig. 5, so that the ports become covered by the packing and consequently the chambers 16, 17 are shut off 70 from the branch pipes and these from one another. For the purpose of making the radiator cold the valve 9 is lengthened at its free end beyond the casings 4, 6 and this extension 20 is provided with ports 21, 22 75 so placed that, when the valve is pushed into the position shown in Fig. 6, these ports are in open relation with the pipes 7, 8 of the radiator and the other ports 12, 14 and 13, 15 open into the atmosphere, so that not 80 only the radiator is connected with the atmosphere, but the connection between it and the heating pipe 1 is quite interrupted, so that no steam can possibly flow into it.

Fig. 7 shows a valve which is not divided longitudinally, as in the hereinbefore described constructional form, but transversely by a wall or partition 23 into two adjacent chambers 16, 17, serving as ducts, of which each has a branch pipe 7, 8, respectively, to which the radiator is connected by means of flexible tubes or the like. In the position of the valve when the radiator is to be heated the steam flows out of the main pipe 1 through the branch pipe 2 and the 95 port 12 into the chamber 16, thence through the branch 7 to the radiator, when it returns through the branch 8 into the chamber 17, and thence through the port 13 and the branch pipe 3 into the pipe 1. By shifting 100 the valve 9 longitudinally its ports can be partially closed, or, for the purpose of shutting off the heat from the radiator, entirely closed, and, when displaced still further longitudinally, connected with the atmosphere, 105 in which event the radiator is connected with the atmosphere by way of the two branches 7 and 8, the two chambers 16 and 17 and the ports 12, 13 which now open into the open air, while the ends of the pipes 2, 3 110 are tightly closed by the valve.

The form of regulator represented in Fig. 8 differs from that just described only in the two boxes 4, 6 of the valve shown in Fig. 7 being united to form one member, the mode 115 of operation of the regulator being exactly the same. These two forms of valve shown in Figs. 7 and 8 are particularly suitable when the radiators are at a somewhat considerable distance from the main heating 120 pipe.

What we claim as our invention and desire to secure by Letters Patent is:

1. In heating apparatus of the character described, the combination of a main pipe 125 having a flow branch and a return branch, and a radiator having a flow pipe and a return pipe, guiding means connected with the said branches of the main pipe, a longitudinally displaceable tubular valve divided 130

into two chambers and guided by said guiding means, one of said chambers adapted to connect in open relation by its ports the said flow branch of the main pipe with the 5 said flow pipe of the radiator, and the other of said chambers adapted to connect in open relation the said return pipe of the radiator with the said return branch of the main pipe to cause a separation of the flow 10 passage of the heating medium through the valve from the return passage of the said medium both in full-opened position and in regulating position of the said valve, substantially as described.

15 2. In heating apparatus of the character described, the combination of a main pipe having a flow branch and a return branch, and a radiator having a flow pipe and a return pipe, means connecting said branches 20 and pipes, a longitudinally displaceable tubular valve guided by said connecting means and divided into two longitudinal, concentric, separated chambers, each chamber having two ports, one of said chambers connecting normally by its ports the said flow branch with the said flow pipe, and the other of said chambers connecting normally by its ports the said return pipe with the said return branch to permit the flow of the 25 heating medium through the radiator to be regulated without connecting the flow branch with the return branch, substantially as described.

3. In heating apparatus, of the character 30 described, the combination of a main conduit for conducting the heating medium, a flow branch and a return branch connected therewith, a radiator having a flow- and a return branch, valve guiding means connected with said two sets of flow- and return branches, said guiding means containing a valve member having two chambers and two ports for each chamber, one chamber connecting in suitable valve position by its ports the flow branches, and the other 35 chamber connecting by its ports simultaneously the return branches of said two sets, said valve member being movably disposed to open and close said ports against said branches and adapted to also open all 40 of said chamber ports and radiator branches to the outside, while the conduit branches remain closed.

to open and close all of said ports simultaneously against said branches. 50

4. In heating apparatus, of the character described, the combination of a main conduit for conducting the heating medium, a flow branch and a return branch connected therewith, a radiator having a flow- and a return branch, valve guiding means connected with said two sets of flow- and return branches, a valve member guided in said guiding means and divided by a longitudinal wall into two chambers, each chamber having two ports, one chamber connecting in suitable valve position by its ports the flow branches, and the other chamber connecting by its ports simultaneously the return branches of said two sets, said valve 55 member being movably disposed to open and close said ports against said branches, substantially as described. 60

5. In heating apparatus of the character described, the combination of a main conduit for conducting the heating medium, a flow branch and a return branch connected therewith, a radiator having a flow- and a return branch, valve guiding means connected with said two sets of flow- and return branches, said guiding means containing a valve member having two chambers and two ports for each chamber, one chamber connecting in suitable valve position by its ports the flow branches, and the other 70 chamber connecting by its ports simultaneously the return branches of said two sets, said valve member being movably disposed to open and close said ports against said branches and adapted to also open all 75 of said chamber ports and radiator branches to the outside, while the conduit branches remain closed. 80

In testimony whereof we have signed our names to this specification in the presence 85 of two subscribing witnesses.
